UNITED STATES PATENT OFFICE

MILTON F. WILLIAMS, OF ST. LOUIS, MISSOURI, ASSIGNEE TO WILLIAMS PATENT CRUSHER AND PULVERIZER COMPANY, OF ST. LOUIS, MISSOURI, A CORPORATION OF MISSOURI.

CRUSHER AND PULVERIZER.

1,020,386.

Specification of Letters Patent. Patented Mar. 12, 1912.

Application filed October 1, 1910. Serial No. 534,866.

To all whom it may concern:

Be it known that I, MILTON F. WILLIAMS, a citizen of the United States, residing at St. Louis, Missouri, have invented a certain new and useful Improvement in Crushers and Pulverizers, of which the following is a full, clear, and exact description, such as will enable others skilled in the art to which it appertains to make and use the same, reference being had to the accompanying drawings, forming part of this specification, in which—

Figure 1 is a vertical longitudinal sectional view through the casing of a crusher and pulverizer, the disintegrating mechanism being shown in elevation. Fig. 2 is a side elevation having part of the casing broken away to illustrate the interior parts. Figs. 3, 4 and 5 are details of construction.

20 This invention relates to the general art of crushers and pulverizers and especially to that class of machines in which the disintegrating mechanism is comprised of pivoted hammers or shredders mounted between 25 rotating disks.

One of the objects of my present improvement is to provide a metal detector. It has been found by experience that very often drill points or metallic bars of various sorts 30 and descriptions are introduced along with the coal, rock or shells to be pulverized or disintegrated. These foreign substances as they knock around in the cage are likely to break some of the parts. My improved machine provides a device arranged in the casing so as to be struck by such hard metallic substances as the hammers are rotated and broken thereby indicating the presence of this foreign and objectionable material, in 35 the machine, which can then be removed.

Another object of my invention is to provide a cleaning device to be passed over the outside of the upper part of the cage to prevent clogging of the openings between the bars of the cage.

Yet another object of my invention is to provide an improved form of dust deflector which is adapted to direct the dust and flying particles in the cage toward the center thereof.

Still another object of my invention is to improve the form of hammer or shredder, by forming them in two parts, the head portion being separated from the shank portion, and both being shaped so that the pres-

sure on the head will be carried longitudinally of the shank.

Referring to the drawings 1 designates a hopper with a suitable chute attached adapted to discharge into the cage. The 60 cage 2 is provided with an entrance 3 under the hopper having at one side thereof a breaker plate 4, and a grinding surface 5 having a removable portion 6. The grinding surface extends to substantially the lowest point in the machine, and is supported 65 in place by a suitable cast member 7.

Riveted or bolted to the casting 7 is an additional cast piece 8 providing a recess 9, and a projecting lip 10 forming a support 70 for a detector plate 11. Extending from a point in proximity to the lip 10 is another section of the grinding surface 12, which is formed by a series of bars 13, so placed as to have openings extending therebetween. 75 This surface 12 extends to a point in proximity to the opening of the cage 3, where it is connected with the dust deflector 14 in the shape of a casting having a chamber 15, said chamber having a back deflecting surface 16 80 curved toward the interior of the cage.

Extending exteriorly of the cage 2 is a suitable cast base or support 17 with a top member 18, which serves as a support for the hopper 1. Connected to the dust deflector 14 and passing at some distance over the top of the cage and down the under side connecting with the cap 18 is a casing 19. This provides an inclosure for substantially 85 the entire exterior of the cage.

Suitably supported exteriorly of the machine is a shaft 20 having a drive pulley 21 connected by a belt with a shaft 22 mounted in the casing 17, extending through the center of the cage 2. Keyed to this shaft are 90 two disks 23 having a series of rods 24 extending therebetween upon which are pivoted a series of hammers or shredders 25 formed with a shank portion 26 and a head portion 27. As disclosed the shank is comprised of a 95 sheet of flat material twisted at right angles to form a flange which is slightly curved as indicated in Fig. 1. The head of the hammer 27 is comprised of a 100 cast piece curved in crescent-shape and having a curved slot fitting over the curved portion 28 of the shank of the hammer. These 105 two parts 27 and 28 are connected together by rivets 29.

Mounted rotatably in the upper frame 116

work and casing 18 and 19 are three shafts 30, 31 and 32 upon which are fixed three gears 33, 34 and 35 adapted to engage with a continuous conveyer 36. As shown in Fig. 4 this conveyer is comprised of chains with a series of links 37 having hooked ends 38, to engage with the succeeding links.

Connected to the opposite sides of certain of the links is a bracket 39 having a flange 40 to which is riveted at 41 an angle piece 44. This angle piece extends from one chain 36 to a similar chain 36' on the opposite side of the machine.

As shown in Fig. 1 the chains 36 and 36' 15 are made loose enough so that the angle pieces 44 may bear against the exterior of the cage 13 as they pass from the shaft 30 at the bottom and one side of the top piece 18 to the shaft 32 on opposite side of the casing 20 ing.

In order that the tension of the chains may be adjusted I provide suitable adjustable brackets for shaft 32 being comprised of bearings 42 attached to adjustable side 25 pieces 45, having slots 46 engaged with bolts 47, projecting from the casing 19. It is obvious that the bracket 45 may be shifted with the shaft 32 and the bolts 47 clamped to hold the same in a position to retain the 30 chains 36, 36' in a taut condition. The shaft 30 is connected with the shaft 20 by means of a belt drive 48.

The detector bar or piece 11 consists of a body portion having a lip shaped to fit the 35 end 10 of the cast piece 8. On the opposite side from this lip or projection are lips 50 formed very thin to be easily broken. Such lips are shown in Fig. 2 projecting from either end of the bar 11. A hook-shaped 40 member 51 is cast solid with the bar 11 substantially at the center thereof. Pivoted on rod 52 is a weighted arm 53, and attached also on the pivot rod 52 is the lever 54 connected by a chain 55 to the hooked 45 arm 51.

The operation of my device is as follows:— The material to be acted upon, crushed or pulverized, is introduced into the hopper and passes down over the breaker plate 4, 50 where it is engaged by the hammers first to be broken. It then passes down over the corrugated crushing surface 5 to be further crushed and then passes onto the perforated surface 12 where it gradually passes through 55 the openings between the bars 13, if properly crushed, and is delivered, if desired, to a proper receptacle within the casing 17. If however, it is carried up so as to be forced out through the openings between the bars at 60 the upper portion of the cage 2 it is engaged by the continuous conveyer formed by the angle pieces 44 and removed from the outside of the cage and carried around to be delivered at one side of the casing 17. The 65 dust deflector 14 is provided so that in the

rotation of the hammers as the dust is forced up into the chamber 15, it is then deflected toward the center of the hammers by the wall 16 and drawn by suction in that direction.

In the form of hammer shown the point of the head engages the material and the head is driven in a direction substantially the same as the curved shank and longitudinally thereof so that there is little or no stress on the fastening means of the head to the shank and most of the stress is in a direction longitudinal to the shank, which latter member is shaped to resist it.

If a drill point or metal piece of any description is accidentally fed to the machine it will drop into the opening 9 and will strike against the detector 11 and break the lugs or lips 50. This will cause the plate 11 to fall in the space 9, being drawn by the 85 weighted chain, permitting the weight to drop, which instantly calls the attention of the attendant to the presence of foreign material in the cage. A door 56 is provided in the casing 17 opposite the openings 9 so that the broken detector bar 11 and the foreign substance may be removed and a new detector bar placed in position.

I am aware that minor changes may be made in the construction, arrangement and combination of the various parts of my device without departing from the spirit of my invention the scope of which is indicated in the accompanying claims.

I claim:—

1. In a device of the character described, in combination, a cage having an opening in one wall, a series of hammers rotatably mounted in said cage, and a detector plate having a frangible portion fitted within said opening.

2. In a device of the character described, in combination, a cage having an opening in one wall, a series of hammers rotatably mounted in said cage, and a detector plate having frangible lips engaging one side of the wall of the opening, said plate being fitted within the opening.

3. In a device of the character described, in combination, a cage having an opening in one wall, a series of hammers rotatably mounted in said cage, and a detector plate having oppositely positioned lips engaging one side of the wall of the opening.

4. In a device of the character described, in combination, a cage having an opening in one wall, a series of hammers rotatably mounted in said opening, and a detector plate adapted to fit within said opening, said plate having frangible lip portions engaging one side of the wall of the opening and means for moving said plate if the lips are broken.

5. In a machine of the class described, a cage provided with a pocket, a frangible

plate forming one of the walls of said pocket and yieldable means for normally holding said frangible plate in position.

6. In a machine of the class described, a grinding cage having a pocket formed at its lowermost side, a frangible plate arranged in said pocket, an arm pivoted on the exterior of the machine and connections between the frangible plate and said arm.
10. 7. In a device of the character described, in combination, a cage, rotatable hammers, a breakable detector bar mounted in the cage and means for normally holding said detector bar in position said means comprising a weighted element.
15. 8. In a device of the character described, in combination, a cage provided with perforated and imperforated grinding surfaces, said surfaces being disconnected, a cast piece forming a recess between said grinding surfaces, and a detector bar normally held in position on said cast piece.
20. 9. In a device of the character described, in combination, a cage, rotatable arms mounted within the cage, a detector bar having a breakable portion normally held in position in an opening in the wall of the cage, means for holding said detector bar in
- 25.

position, comprising a weighted arm, and a chain connecting said weighted arm with the detector bar.

10. In a device of the character described, a cage having a series of rotating hammers mounted therein, each hammer comprising a twisted shank portion having a curved end and a head portion slotted to engage the curved end of the shank, said head portion being curved in the direction of rotation of the hammers.

11. In a machine of the class described, a cage provided with a pocket, a fixed plate forming the bottom of said pocket, a frangible plate positioned between the first mentioned plate and the cage, which frangible plate forms one of the walls of the pocket, an arm pivotally arranged on the exterior of the machine and a connection between the frangible plate and said arm.

In testimony whereof I hereunto affix my signature in the presence of two witnesses, this 14th day of September, 1910.

MILTON F. WILLIAMS.
